UNITED STATES PATENT OFFICE.

LUDWIG B. LARSEN, OF PORTLAND, OREGON.

BUTTER-CUTTER.

No. 893,591.

Specification of Letters Patent.

Patented July 14, 1908.

Application filed May 9, 1908. Serial No. 431,977.

To all whom it may concern:

Be it known that I, LUDWIG B. LARSEN, a citizen of the United States of America, residing at Portland, in the county of Multnomah and State of Oregon, have invented certain new and useful Improvements in Butter-Cutters, of which the following is a specification.

The invention relates to an improvement in butter-cutters, being particularly directed to a construction whereby a mass or body of butter may be conveniently divided and subdivided to provide uniformly-sized blocks adapted for individual or table use.

The main object of the present invention is the production of a butter cutter in which the series of cutting elements are made up of a single length of material, the construction providing a simple means whereby said cutting elements may be tensioned to insure a proper cutting effect, the tensioning means being arranged to exert an endwise strain upon the single length of material and thereby simultaneously tension all of the cutting elements formed by said single length of material.

A further object of the invention is the provision of a cutting frame particularly adapted to permit the formation of the cutting elements from the single length of material, said frame being formed to permit the disposition of the cutting elements with any desired degree of relative spacing, whereby to provide butter blocks of the desired size.

The invention in the preferred form of details will be described in the following specification, reference being had particularly to the accompanying drawing, in which:

Figure 1 is a view in side elevation, illustrating the construction and application of my improved butter-cutter. Fig. 2 is a partial plan of the cutter frame. Fig. 3 is an enlarged section on the line 3—3 of Fig. 2. Fig. 4 is a broken plan showing a modified form of cutter-adjusting means. Fig. 5 is an enlarged broken transverse sectional view through the table, illustrating particularly the longitudinal-cutter receiving channel therein.

Referring particularly to the drawings, wherein is illustrated the preferred details of construction, my improved butter-cutter comprises a base 1, of approximately rectangular construction, and formed with a smooth upper surface 2, hereinafter referred to as the table.

Centrally of and extending beyond each end wall of the base there is provided a block 3, from which rises an upright 4. The uprights 4 extend above the table of the base and are adapted to provide guide rods for insuring a proper movement of the cutter frame in the cutting operation.

The cutter frame 5 is of skeleton rectangular form and includes side bars 6 and 7 and end bars 8. The end bars are integrally formed by preference with one of the side bars, as 6, the remaining side bar 7 forming a distinct and separate part. The terminals of the end bars 8 are formed with extensions 9 and 10 arranged to provide guide flanges for the movement of the side bars 7 of the frame in the adjustment of the latter to be later described. The flange 9 of each end bar extends in alinement with the lower surface of the bar, while the flange 10 extends in alinement with the relatively outer side of the bar, so that the flanges 9 and 10 form in effect a right angled support for the bottom and ends of the side bar 7.

The side bar 7 is, in addition to its duplication of the structure of the side bar 6, which will be later described, formed with end extensions 11, which on their bottom and end surfaces are squared to bear squarely on and against the flanges 9 and 10 of the respective end bars. The extensions 11 are formed with transverse openings 12, interiorly threaded for the reception of thumb screws 13, the terminals of which are adapted to seat in openings 14 longitudinally arranged in the free terminals of the end bars 8.

By the construction described it will be understood that operation of the thumb screws 13 may be had to cause the side bar 7 of the frame to approach or recede from the side bar 6, thereby decreasing or increasing the transverse dimension of the frame. During such adjustment the side bar 7 is guided in the flanges 9 and 10, thereby insuring alinement of the end bars and side bar 7 so far as any endwise or downward strain on the side bar 7 is concerned.

Aside from the particulars of the extensions 11 the side bars 6 and 7 are of identical construction, the transverse sectional view of one of said bars being shown in Fig. 3. Each bar is preferably rounded on its relatively inner edge, and is formed in its bottom edge with a series of grooves or channels 15, extending transversely of said edge and throughout the width of the same. The

relatively outer edge of each bar is formed with a series of parallel spaced projections 16, the upper edge of each of which projections is formed into a depressed curve or cavity 17, leaving the end of the projection in the form of a horn 18 which extends to a slight extent in an upward direction.

The channels 15 are preferably in greater number than the projections 16, the arrangement shown in Fig. 1 including a channel in alignment with the side edge of each projection, so that each projection co-operates with a pair of channels.

Each end bar 8 is centrally formed with a downwardly extending lug 19, which is preferably rounded on its relatively outer surface and projected in alignment with the relatively inner surface of the bar. The outer edge of each end bar is formed to provide a bearing member 20, the arms of which are arranged to partly encircle the guide rods 4 of the base, whereby reciprocal movement of the cutter frame with relation to the base is provided for on fixed lines. For convenience in casting the bearing members 20 are in the form of interrupted annular sections, though it is to be understood that they may be otherwise formed if desired. Each end bar is also provided with a handle member 21 projecting outwardly and upwardly from the bar for convenience in operating the frame.

In the preferred form of the invention the cutter comprises a single length of wire 22, which is terminally secured to one of the lugs 19, then projected longitudinally of the cutter frame to provide a central and longitudinal cutter 23, then passed around the other lug 19, then projected laterally to one of the side bars, as 7, through the adjacent end channel 15 in said bar, upwardly and over the horn 18 of the adjacent projection 16, then fitted in one of the channels 15 adjacent said section 16, then transverse the cutter frame to provide a cross-cutter 24, then fitted in one of the channels 15 of the opposing side bar, as 6, up and over the adjacent horn 18, and back across the cutter frame to form the next cross cutter. The operation of stringing the wire to provide the cross cutters, as above described, is continued until all of the cross cutters are formed, the terminal of the wire being secured to the last projection 16 by any desired form of tie.

By the method of stringing described, and also by the arrangement of the channels and projections, it is obvious that any desired spacing of the cross cutters may be secured by utilizing adjacent or spaced channels 15 for the direct and return strands of the wire length, thus providing for cutting the blocks of butter in any desired thickness.

After stringing of the wire length as described, operation of the adjusting screws 13 will tend to force the cross bar 7 from the cross bar 6, thereby straining and properly

tensioning the cross cutters 24, the single length of material from which the cutters are formed yielding endwise during such straining and thereby simultaneously and uniformly tensioning all of the cutters.

As shown in Fig. 5 the table 2 of the base is formed with a central and longitudinal channel 25, which is approximately of semi-circular form in transverse section. This channel is adapted to receive the longitudinal cutter 23 in the operation of the device, whereby the cross cutters may be forced down into full contact with the table and thereby insure a complete severing of the butter mass.

In operation the body of butter, preferably in the ordinary commercial block, is placed upon the table 2, and the bearing members 20 of the cutter frame slidably engaged with the guide rod 4. The downward movement of the frame causes the respective cutters to divide the body of butter into a series of uniform blocks, as will be evident.

In Fig. 4 I have shown a slightly modified form of means for adjusting the wire length forming the cutters. In this form said wire length, as 26, is positioned on the cutter frame as in the preferred form, with the exception that said wire length is adapted to provide a portion only of the total number of cutters. In this form one end of the wire length is secured to one of the projections, the remaining end being fixed to and adapted for coiling about a thumb screw 27 threaded in an opening 28 formed in one of the side bars. By adjustment of the thumb screw the wire length may be strained and all the cutters formed thereby suitably tensioned. It is, of course, understood that in this form the cutter frame is a solid structure and that as many wire lengths and set screws as may be necessary to provide the desired number of cutters are to be used.

The various parts of the device are preferably constructed of metal, which is to be so finished as to avoid affecting the butter material, as for instance by nickel plating or the like.

The device is to be constructed of any desired size, and while preferring the metallic construction contemplate the use of any material which may be found efficient.

Having thus described the invention what is claimed as new, is:—

1. A butter - cutter including a cutter frame, a series of cutters arranged transversely of the frame, and means for adjusting a portion of the frame to simultaneously tension all of said cutters.

2. A butter - cutter including a cutter frame, a single length of material connected to said frame to provide a longitudinal cutter and a series of transverse cutters, and means for adjusting a portion of the frame to simultaneously tension all of said cutters.

3. A butter - cutter comprising a cutter frame including side and end bars, means for adjusting one of said side bars with relation to the other, and a series of cutters connecting the side bars.
4. A butter - cutter comprising a cutter frame including side and end bars, means for adjusting one of said side bars with relation to the other, and a series of cutters connecting the side bars and constructed of a single length of material.
5. A butter - cutter comprising a cutter frame including side and end bars, means for adjusting one of said side bars with relation to the other, a longitudinal cutter connecting the end bars, and a series of cross cutters connecting the side bars, said longitudinal cutter and cross cutters being constructed of a single length of material.
6. A butter - cutter comprising a cutter frame including spaced side bars, each of said bars being formed in the lower edge with a series of transverse channels, and a series of outwardly extending projections carried by each bar, each of said projections being formed to provide a retaining horn.
7. A butter - cutter comprising a cutter frame including spaced side bars, each of said bars being formed in the lower edge with a series of transverse channels, and a series of outwardly extending projections carried by each bar, each of said projections being formed to provide a retaining horn, and a single wire length extending across the frame and fitted in the channels and about the horns of the respective side bars.
8. A butter-cutter including a base formed to provide a table, a cutter frame mounted for movement to and from the base, means for guiding said frame during such movement, a series of cross cutters carried by the frame, a longitudinal cutter carried by the frame, said cross cutters and longitudinal cutter being constructed of a single length of

material, the table of the base being formed with a longitudinal channel to receive the longitudinal cutter in the operative movement of the frame.

9. A butter-cutter comprising a base, guide rods carried thereby, and a cutter frame arranged to engage the guide rods and adapted for movement to and from the base, said cutter frame comprising side bars formed with transverse channels and projections, and end bars formed with central depending lugs, and a single length of wire secured to one of the lugs, projected longitudinally of the frame and engaged with the remaining lug, and then transversely of the frame to provide a series of cross cutters, the transverse projections of the wire length seating in the channels and engaging the projections of the respective cross bars.

10. A butter - cutter comprising a base, guide rods carried thereby, and a cutter frame arranged to engage the guide rods and adapted for movement to and from the base, said cutter frame comprising side bars formed with transverse channels and projections, and end bars formed with central depending lugs, a single length of wire secured to one of the lugs, projected longitudinally of the frame and engaged with the remaining lug, and then transversely of the frame to provide a series of cross cutters, the transverse projections of the wire length seating in the channels and engaging the projections of the respective cross bars, and means for adjusting one of the side bars with relation to the other to simultaneously tension all of said cutters.

In testimony whereof I have affixed my signature in presence of two witnesses.

LUDWIG B. LARSEN.
